CLAIM

The ornamental design for a pair of open door/window sensors, as shown and described.

DESCRIPTION

FIG. 1 is a front view of a pair of open door/window sensors, showing our new design;

FIG. 2 shows a side perspective view thereof.

FIG. 3 shows a perspective view of one of the pair of open door/window sensors.

FIG. 4 shows a perspective view thereof.

FIG. 5 shows a rear view thereof.

FIG. 6 shows another perspective view thereof.

FIG. 7 shows another perspective view of one of the pair of open door/window sensors.

FIG. 8 shows another perspective view thereof.

FIG. 9 shows a bottom view thereof; and,

FIG. 10 shows a top view thereof.
